COMBINED SUCTION CLEANER HOSE CONNECTION AND SUPPORT

Van William McKnab, Ponca City, Okla., assignor to
Vacu-Maid, Inc., Ponca City, Okla., a corporation of
Oklahoma

Filed Apr. 1, 1963, Ser. No. 74,234

Term of patent 14 years

(Cl. D9—2)

FIG. 1 is a perspective view of a combined suction cleaner hose connection and support embodying my design, the cap on the hose connection portion being in open position.

FIG. 2 is a front elevational view thereof.

FIG. 3 is a side elevational view, the opposite side being a mirror image thereof.

FIG. 4 is a rear elevational view thereof.

FIG. 5 is a top view thereof.

Portions shown in broken lines are included for illustrative purposes only.

I claim:

The ornamental design for a combined suction cleaner hose connection and support, as shown and described.
